HATCHET

Sigvald Troell, Solleftea, Sweden, assignor to
 Sandvikens Jernverks Aktiebolag, Sandviken,
 Sweden, a registered company of Sweden

Application May 21, 1934, Serial No. 726,849
 In Sweden June 15, 1933

7 Claims. (Cl. 30—11)

The present invention relates to a hatchet to be used for felling small trees in connection with clearing operations, for pruning purposes, for disbranching and unbarking felled timber, and for similar purposes. For work of this kind, hatchets provided with ordinary wedge-shaped hatchet-head have been found to be less suitable, partly because for a certain required length of cutting edge the hatchet head becomes unnecessarily big and heavy, and partly because the wedge-shape causes increased frictional resistance against the hatchet head when the latter penetrates into the wood between the two cut surfaces. The frictional forces set up occur mainly in the surfaces of the portion of the hatchet connecting the cutting-edge and the rear part of the hatchet head, the so called hammer, which portion increases in thickness from the cutting edge to the hammer.

The above mentioned inconveniences are all avoided according to the present invention by providing a hatchet the head of which can be made arbitrarily heavy independently of the length of the cutting-edge and in which the wedge-shaped portion between the cutting-edge and the hammer is entirely dispensed with, which is rendered possible substantially thereby that the hammer of the hatchet is designed as a substantially yoke-shaped frame having the mass required for the hatchet head, a knife-shaped hewing blade forming the cutting edge of the hatchet being secured between the arms of said yoke.

The invention will be described in the following with reference to the accompanying drawing, on which

Figure 1 shows a side view of a hatchet according to the invention, and

Figure 2 shows a detail of the fixing means for the cutting member.

According to the embodiment shown on the drawing the hatchet consists of the frame 1, the cutting member 2, and the handle 3. The frame 1 preferably consists of a resilient flat iron bent in U-shape, the arms 4, 5 of the frame being adapted to be sprung inwardly. The free ends of the arms are provided with slots 6 adapted to receive the cutting member 2. Said cutting member consists of a comparatively thin blade having a considerably greater length than width and formed with a cutting edge, said blade being provided at its ends with fixing members 7 consisting of transverse pins secured in the outer blade ends and adapted, when the blade is in

position in the slot 6, to bear against the outer sides of the arms 4, 5 of the frame. The arms are provided with notches 8 for receiving the pins 7.

The distance between the pins 7 of the cutting member is smaller than the distance between the notches 8 in the arms when the frame is in a non-sprung position. When the cutting member is inserted in the frame the arms must therefore be sprung towards each other in order that the pins shall be able to take up their positions in the notches 8. For the purpose of facilitating the insertion of the cutting member in the frame one of the arms, preferably the arm 4, is so shaped that its outer end tapers and forms a sliding surface 9 for the corresponding pin 7 whereby the springing of the frame is also facilitated.

After the cutting member has been placed in position it is held in place on account of the resilience of the frame and is at the same time subjected to a suitable tension.

In ordinary hatchets it is a common occurrence that the outer ends of the cutting edge are destroyed on account of the hatchet during handling cutting into stone. This risk is reduced in a hatchet according to the present invention thereby that the free ends of the arms are so long as to project beyond the cutting edge 10 of the cutting member and thus to form a protection for the same.

For the purpose of lengthening the duration of life for each cutting member the cutting member is provided, in addition to the ordinary edge 10, with an opposite edge 10a so that when one edge has become blunt the other may be brought into operating position simply by turning the cutting member. For certain purposes it may be desirable to use instead of a straight cutting edge of any known type a convex edge. Also in some cases the cutting member may if desired be made with one straight edge and one convex edge.

On account of the comparative smallness of the cutting member and its small weight a sufficient number of such members may on expeditions be brought along as spares to replace worn ones when necessary. This is an additional advantage in comparison with ordinary hatchets, the grinding of which in the field is often connected with difficulties.

Experience has shown that the efficiency of the hatchet is increased if the cutting member is not arranged parallelly with the handle. For this

purpose the longitudinal axis of the cutting member and of the handle form an angle with each other whereby the cutting power of the hatchet is increased.

5. The handle 3 is preferably made of a suitable kind of wood and is secured to the frame 1 by means of riveted-on or welded-on fixing means.

10. The cutting member is easily detached from the frame by inserting between the frame and the back of the cutting member an angular fixed object for example a stump 13 of a suitable cross section, and then exerting a turning moment on the cutting member by means of the handle, whereby the cutting member while overcoming the spring power of the frame can be easily removed therefrom.

15. The invention is not limited to the embodiment described above and shown on the drawing but can be modified in many respects without receding from the idea of the invention. Thus the arm 5 farthest from the handle 3 may be formed without a notch 8, whereby removal of the blade 2 is facilitated, the upper pin 7 being brought on removal to slide along the outer surface of said arm 5 while the lower pin 7 remains in its corresponding slot 8 and serves as a pivot for the blade.

I claim:—

30. 1. An axe comprising a head and a handle, said head consisting of a resilient bail-shaped frame having the mass required for an axe head and a knife-shaped hewing blade forming a cutting member and having fixing members at the ends thereof, the frame including diverging arms 35 adapted to cooperate with said fixing members and provided at their ends with slots adapted to receive the cutting member so that the cutting member is held in spaced relation to the medial portion of said bail-shaped frame and in position 40 in the slots and bears against the bottom of said slots.

45. 2. An axe comprising a head and a handle, said head consisting of a resilient bail-shaped metallic frame having the mass required for an axe head and a knife-shaped hewing blade forming a cutting member, said cutting member including fixing members provided at the ends thereof, the frame including diverging arms provided at their 50 ends with slots adapted to receive the cutting member so that the cutting member bears against the bottom of said slots, whereby said fixing members cooperate with the outer side surfaces of said diverging arms of the resilient frame, the cutting member being held in position in spaced 55 relation to the medial portion of said bail-shaped frame by the resilience thereof.

60. 3. An axe comprising a head and a handle, said head consisting of a resilient bail-shaped metallic frame having the mass required for an axe head and a knife-shaped hewing blade forming a cutting member, said cutting member including fixing members at the ends thereof, the frame including diverging arms provided at their ends 65 with slots adapted to receive the cutting member so that the cutting member bears against the bottom of said slots, said diverging arms being provided with notches on their outer side surfaces adjacent the slots whereby said fixing members cooperate with said notches and the cutting member is held in position in spaced relation to the

medial portion of said bail-shaped frame by the resilience thereof.

4. An axe comprising a head and a handle, said head consisting of a resilient bail-shaped metallic frame having the mass required for an axe head, and a knife-shaped hewing blade forming a cutting member, said cutting member being reversible and provided with cutting edges on both sides and including fixing members at the ends thereof, the frame including diverging arms 5 provided at their ends with slots adapted to receive the cutting member so that the cutting member bears against the bottom of said slots whereby said fixing members cooperate with the outer side surfaces of said diverging arms of the 10 resilient frame, the cutting member being held in place with either cutting edge in operative position by the resilience of the bail-shaped frame.

5. An axe comprising a head and a handle, said head consisting of a resilient bail-shaped metallic frame having the mass required for an axe head and a knife-shaped hewing blade forming a cutting member, said cutting member including transverse pins provided at the ends thereof, the frame including diverging arms provided at their 20 ends with slots adapted to receive the cutting member so that the cutting member bears against the bottom of said slots whereby said transverse pins cooperate with the outer side surfaces of said diverging arms of the resilient frame, the cutting member being held in position by the resilience of the bail-shaped frame and the diverging arms of the frame projecting beyond the cutting member for the purpose of protecting the cutting edge thereof.

30. 6. An axe comprising a head and a handle, said head consisting of a resilient bail-shaped metallic frame having the mass required for an axe head, and a knife-shaped hewing blade forming a cutting member, said cutting member including 40 transverse pins at the ends thereof, the frame including diverging arms provided at their ends with slots adapted to receive the cutting member so that the cutting member bears against the bottom of said slots, whereby said transverse pins 45 cooperate with the outer side surfaces of said diverging arms of the resilient frame, the cutting member being held in position by the resilience of the bail-shaped frame, one of said diverging arms being provided at its outer end with a beveled surface converging toward the outer end of the other arm of the bail-shaped frame, over which beveled surface the corresponding transverse pin of the cutting member slides when the cutting member is inserted in position in the slots 50 of the frame.

55. 7. A hand axe comprising a handle and a head formed as a strip-like resilient bail-shaped member secured to the handle and including an intermediate portion and spaced diverging arms, the outer ends of which are slotted and a knife-shaped cutting member having fixing members at the ends thereof cooperating with said diverging arms inserted in the slotted ends of the diverging arms of said bail-shaped member and held in fixed position by the fixing members in such a manner that the cutting member is positioned in spaced relation to the intermediate portion of said bail-shaped member.
